UNITED STATES PATENT OFFICE

114,831

DESIGN FOR A CASING FOR DOOR CLOSING
AND CHECKING DEVICE OR SIMILAR
ARTICLE

Louis F. Schmidt, Chicago, Ill., assignor to Norton Lasier Company, Chicago, Ill., a corporation of Illinois

Application March 19, 1938, Serial No. 75,948

Term of patent 7 years

To all whom it may concern:

Be it known that I, Louis F. Schmidt, a citizen of the United States, residing in Chicago in the county of Cook and State of Illinois, have invented a new, original, and ornamental Design for a Casing for Door Closing and Checking Device or Similar Article, of which the following is a specification, reference being had to the accompanying drawing, forming part thereof.

Figure 1 of the drawing is a perspective view of a casing showing my new design; and Figure 2 is a reduced bottom view of the casing shown in Figure 1.

In the drawing, the top and back are not shown, as these portions are plain. The casing as represented in Figure 1 has the same appearance when shown in the opposite perspective.

I claim:

The ornamental design for a casing for door closing and checking device or similar article, substantially as shown and described.

LOUIS F. SCHMIDT.
